TO THE OHIO BOXBOARD COMPANY, OF CLEVELAND, OHIO, A CORPORATION OF
OHIO.

METHOD OF AND APPARATUS FOR FORMING THE BLANKS FOR FOLDED BLANK BOXES.

Application filed December 15, 1926. Serial No. 155,023.

This invention relates to a method of and apparatus for producing blanks for folded-blank boxes and the like containers, such as that shown and described in our application for patent for corner seals for boxes, Serial No. 155,024, filed of even date herewith, and in which means is provided in the blanks themselves for closing the corners of the containers when the blanks are folded and closed to form the complete containers.

The object of the invention is to produce by a single operation of the blank forming apparatus, a blank which, when folded to produce the completed container for which it is designed, will include means integral with the material of the container for closing the corners thereof, so that the container will be suitable for the packaging of pulvulent, granular and flaky substances and will have its corners so sealed that such substances cannot sift therefrom, and that vermin cannot find access therethrough to the interior of the container.

The invention consists in a method of forming the blanks for folded-blank boxes whereby the corners thereof will be sealed, comprising the formation of incisions in various of the sealing flaps of the blanks for such boxes, which when the blank is folded and the flaps closed, will produce a web closing each corner of the box; and the invention consists further in the apparatus for carrying out this method, as we will proceed now to explain and finally claim.

In the accompanying drawings illustrating the invention, in the several figures of which like parts are similarly designated, Figure 1 is a plan view of a blank of the type contemplated by our invention. Fig. 2 is a perspective view showing the blank folded and partially closed. Fig. 3 is a section taken on the line 3-3 of Fig. 1. Fig. 4 is an enlarged detail perspective view of one of the corner sealing webs. Fig. 5 is a somewhat diagrammatic side elevation of a cylinder cutting-press of the type ordinarily used in cutting box blanks, and to which our apparatus may be applied in the carrying out of the method of our invention. Fig. 6 is a plan view of the matrix of our apparatus, and Fig. 7 is a plan view of the cutting and scoring die complementary thereto. Fig. 8 is a fragmentary section, greatly enlarged, taken on line 8-8 of Fig. 7.

The blank shown in Fig. 1, and which is typical of those produced by our invention, comprises broad sides 1 and 2 and narrow sides 3 and 4, the broad side 1 having formed integral with it a pasting flap 5 which, when the blank is folded to form a box, is pasted along the free edge of the narrow side 4. All of these divisions of the blank are formed by the vertical creases or scores 6 and longitudinal creases or scores 7. Extending from the broad sides 1 and 2 at both ends are end sealing flaps 8, 8 and 9, 9 respectively, and extending from the narrow sides 3 and 4 at both ends, are end sealing flaps 10, 10 and 11, 11, respectively. All of these sealing flaps are foldable upon the creases or scores 7 and are defined by cuts 12.

In order to provide means for positively sealing the corners of the containers formed from blanks of this general character, we terminate the cuts 12 at a short distance 75 from the creases or scores 5 and join their ends to these creases by diagonal cuts or incisions 13 which extend only part way through the material of the blank from the inner side *a* thereof, as indicated in Fig. 3. 80 On the outside *b* of the blank the cuts 12 are joined to the creases or folding lines 5 by cuts or incisions 14, indicated in light dotted lines in Fig. 1 and by a full line in Fig. 3, which extend only part way through the material of the blank from the outer side *b* thereof. 85

It is in the method of and apparatus hereinafter fully explained, for forming the cuts or incisions 13 and 14, that our invention 90 particularly resides.

By providing the cuts or incisions 13 and 14, it is possible, during the folding of the blank to form a box or container, to produce webs of the material of the blank at all 95 of the corners of the box to completely seal the corners. In order that this may be fully understood, the blank is folded as follows:— First, the pasting flap 5 is folded inwardly along its adjacent crease or score 6 and 100 pasted to the inner face of the narrow side 4, as hereinbefore indicated, with its fold on the crease 6 lying along the edge *c* of the side 4. Then the thus pasted blank is bent upon the creases or scores 6 to rectangular form. 105 Then the sealing flaps 10 and 11 are bent inwardly toward each other as indicated in Fig. 2. It is at this point in the operation

of folding the blank into box-forming condition that the corner sealing means becomes operative. As will be seen, by reference to Figs. 2 and 4, when the sealing flaps 10 and 11 are bent inwardly toward each other, the material of the blank strips or peels between the cuts or incisions 13 and 14 because one of its faces, the inside face *a*, is left attached both to one of the broad sides of the blank and to the flap being folded. This stripping or peeling of the material substantially midway of its thickness, forms a web 15, Figs. 2 and 4, at each corner of the box, which, when the sealing flaps 8 and 9 are folded down upon the previously infolded flaps 10 and 11 and securely pasted, will completely close and seal the corners.

As stated, when the flaps 10 and 11 are folded in, a web 15 closing each corner is formed. Then, when the flaps 8 and 9 are folded down upon the flaps 10 and 11 and upon each other and pasted, a crimp or fold is formed in each of the webs 11 and they become pasted to the adjacent adhering faces of the flaps 8 and 9.

The method of forming the corner seal of the container resides in the provision at the junction of the sides and end sealing flaps thereof of incisions extending only part way through the material of the blank, which, when the blank is folded, result in stripping or peeling of the material of the blank substantially midway of its thickness between such incisions, whereby the webs are formed at the several corners of the box.

The method of our invention may be carried out upon any kind of press ordinarily used for cutting and creasing paper box blanks, such as a cylinder cutting-press, of substantially the type illustrated in Fig. 5, by employment of apparatus embodying certain modifications of the elements ordinarily used in forming blanks upon presses of this character, as will now be described. In this connection, attention is directed particularly to Figs. 5, 6, 7 and 8.

In Fig. 5, we have shown, somewhat diagrammatically, the parts of a cylinder cutting-press, essential to the carrying out of our invention, as follows:—Reference character 16 designates a frame carrying a plurality of rollers 17 upon which is mounted a bed 18 carrying a rack 19 which meshes with a mutilated ring gear 20 carried by the cylinder 21. The cylinder 21 has an adjustable bearing 22 in a stand 23 of the frame 16 whereby the height of the cylinder above the top of the bed 18 may be adjusted. All of these parts are of ordinary construction, and so function that when the cylinder 21 rotates, the gear 20 in meshing with the rack 19 will move the bed 18 upon the rollers 17 under the cylinder in the direction of the arrow, and when the gear 20 is out of engagement with the rack 19, the bed will be

returned to the position shown, by other mechanism, not illustrated but of usual construction. At each movement of the bed from left to right, (Fig. 5) a blank-forming operation will be carried out.

In machines of this type, it is customary to mount upon the bed 18 a block or plurality of blocks 24 in each of which are carried knives and scoring or creasing members so arranged with respect to each other as to cut the material operated upon to produce a blank or blanks of the conformation desired. Such a block and its knives and scoring or creasing members form the cutting die. Upon the cylinder is mounted a matrix or plurality of matrices 25 complementary to the cutting die or dies, and formed of material of such flexibility as to be capable of being bent to the curvature of the cylinder. Fibre board is suitable for this purpose.

When a press of the bed and platen type is used, the cutting die will be mounted upon the bed of the press and the matrix upon the platen.

It is in these last mentioned parts of the apparatus, namely, the cutting die and the matrix, that the changes which characterize our apparatus are made.

In Fig. 7 we have shown a plan view of a cutting die for forming the blank illustrated in Fig. 1. This die comprises the wooden block 24, which may be made up of a number of pieces secured together and in which are fixedly mounted the following knives and scoring or creasing members, namely: the knife 26, which makes the complete cut along the left hand edge of the pasting flap 5; the knives 27, which make the cuts at the ends of this pasting flap; the knives 28, which make the cuts 12 completely through the blank; the knives 29 and 30, which make the cuts delimiting the blank at the ends of the sealing flaps 8, 9, 10 and 11 and at the edge *c* respectively; the scoring members 31, which make the folding creases or scores 6, and the scoring members 32, which make the folding creases or scores 7. In addition to the knives and scoring or creasing members just enumerated, we mount in the block short knife sections 33 for forming the cuts or incisions 14 in the blank, these knife sections being arranged in line with the knives 28 but having their cutting edges depressed below the cutting edges of the knives 28 (see Fig. 8), so that in the operation of forming the blank they will cut only part way through the material of the blank.

All of the cutting knives are flanked by resilient members 34, ordinarily formed of rubber or felt and capable of so yielding as to permit the knives to pass through the material of the blank upon pressure thereon of the matrix carried by the cylinder.

The matrix used with our apparatus, and illustrated in Fig. 6, is in most particulars

of ordinary construction. It is formed with grooves 35 and 36 extending into its surface sufficiently to allow the scoring or creasing members 31 and 32, respectively, to crease the material of the blank along the lines 6 and 7, as is usual in apparatus of this character, and is cut away completely at those portions where the various knives are arranged to cut entirely through the blank.

10 A departure from the ordinary practice in apparatus of this character, and which forms one of the novel features of our invention, is the application to the matrix of small knives 37, the edges 38 of which are turned up substantially at right angles to the body portions of same and stand away from the body portions a distance sufficient to cut partway through the material of the blank. These small knives are 15 so angularly arranged and so positioned as to produce the cuts or incisions 13 in the blank. As one means of securing the knives 37 to the matrix, we have shown small pieces of gummed tape 39 affixed to the knives and 20 to the matrix, but other appropriate means might be used, if desired.

In order to produce a yielding surface against which the material of the blank may be forced under the influence of the knives 37, we provide the block 24 with suitably arranged abutments 40, comprising plungers 41 mounted in sleeves 42 supported in the block 24 and having heads 43 backed up by springs 44, whereby they are resiliently 30 supported to yieldingly react to the pressure of the knives 37 against the material of the blank, so that when the cutting edges 38 of the knives 37 have entered the material of the blank and the body portions of the 35 knives are in contact with the blank, no further cutting will take place, the abutments 40 yielding under the pressure applied.

So far as we are aware, it is a complete 40 departure from established practice, in apparatus of this character, to embody in a single installation means whereby a sheet of material may be incised upon both of its sides simultaneously, the difficulties attending such an operation having, we believe, 45 remained unsolved prior to our invention.

Heretofore, where it was desired to produce cuts or incisions upon both sides of a piece of material of the character in question, it was necessary to provide two sets of 50 dies and matrices, the material being cut upon one side by one set and upon the other side by the other set. And it required two separate operations to complete this procedure, the blank being turned over after 55 operation upon it by one set to present its opposite side for operation upon it by the other set.

Obviously, by operating upon both sides 60 of the material simultaneously, we have 65 greatly reduced the cost of manufacture of

such articles by eliminating one set, die and matrix, and one operation.

The operation of our apparatus in the carrying out of our method by the use of a cylinder press of substantially the type illustrated in Fig. 5 is as follows:—The die or dies and matrix or matrices are arranged upon the bed and cylinder of the press, respectively, in such relationship as to exactly register when the cylinder rotates and the bed passes beneath it. The press having been adjusted to operate at the desired speed, sheets of blank-forming material, such as boxboard, fibre-board, and the like, are placed upon the dies when the bed is in the position shown in Fig. 5, and, the press being started, the cylinder will rotate and the bed, with the dies and blank-forming material will pass beneath it, the various knives and scoring means, carried both by the dies and matrices performing the operations, previously described, for which they are designed. Exact register of the dies with the matrices is assured by the meshing of the ring gear 20 with the rack 19. When 70 the cutting and scoring operations have been performed as the dies pass under the cylinder in complementary register with the matrices carried thereby the bed 18 will pass to the right hand end (Fig. 5) of the machine and the finished blanks and scrap will 75 be discharged from the dies, the resilient members 34 acting to disengage the blanks and scrap from the dies after the pressure 80 exerted by the matrices has been released.

It is usual to make the press continuous in its operation throughout a given run, and this being the case, after the blanks and scrap have been discharged from the dies, the bed 18 will be automatically returned to 85 the left of the machine so that it may be supplied with fresh sheets of material and then, in timed relation to the rotation of the cylinder, will again automatically pass under the cylinder when the matrices carried thereby again approach the point of 90 register with the dies.

Thus, on a single machine, with a single set or sets of dies and matrices, we are enabled continuously to produce blanks for 95 folded-blank boxes properly scored and cut and provided with the incisions hereinbefore mentioned, such incisions being formed upon both sides of the material in a single 100 operation upon the material of which the 105 blanks are formed.

Various changes are contemplated as 110 within the spirit of the invention and the scope of the following claims.

What we claim is:—

1. A method of forming the blanks for 115 folded-blank boxes and the like, which includes cutting and creasing said blanks and producing therein incisions on both sides of the blanks at a single operation.

2. A method of forming the blanks for folded-blank boxes and the like, which includes simultaneously cutting and creasing said blanks and producing therein at predetermined points incisions extending only partially through the material of the blank from both faces thereof. 70
3. A method of forming the blanks for folded-blank boxes, which includes cutting and creasing said blanks to form a box of the desired conformation, and producing incisions in said blanks from both faces thereof at predetermined points thereon simultaneously with said cutting and creasing operation. 75
4. A method of forming the blanks for folded-blank boxes, which includes cutting and creasing said blanks to form a box of the desired conformation, and producing incisions in said blanks extending only part way through the material of the blank from both faces thereof at predetermined points thereon simultaneously with said cutting and creasing operation. 80
5. A method of forming a blank for folded-blank boxes and the like containers having a plurality of sides and end sealing flaps carried thereby, which includes producing surface incisions so located adjacent to the juncture of the flaps with the sides that portions of the material of the blank contiguous to the incisions will provide sealing webs when the flaps are folded into sealing position. 85
6. A method of forming a blank for folded-blank boxes and the like containers having a plurality of sides and end sealing flaps, which includes producing surface incisions simultaneously on opposite faces of the blank so located adjacent to the junctures of the flaps with the sides that portions of the material of the blank contiguous to the incisions will provide sealing webs when the flaps are folded into sealing position. 90
7. A method of forming a blank for folded-blank boxes and the like containers having a plurality of sides and end sealing flaps carried thereby, which includes producing diagonally arranged surface incisions so located adjacent to the junctures of the flaps with the sides that portions of the material of the blank contiguous to the incisions will produce sealing webs when the flaps are folded into sealing position. 95
8. A method of forming a blank for folded-blank boxes and the like containers having a plurality of sides and end sealing flaps carried thereby, which includes producing surface incisions so located adjacent to the junctures of the flaps with the sides that portions of the material of the blank contiguous to the incisions will produce sealing webs at the corners of the containers when the flaps are folded into end sealing position. 100
9. Apparatus for producing a blank for forming folded-blank boxes and the like, including a die and a matrix, and means carried by said die and means carried by said matrix, whereby an incision may be made in each side of said blank at a single operation of said apparatus, the incisions being of such character that the material of the blank may peel contiguous to them so as to form webs to close the corners of the box formed from the blank. 105
10. Apparatus for forming a blank for folded-blank boxes and the like having a plurality of sides and end sealing flaps carried thereby, including a die and a matrix, a knife carried by said die and a knife carried by said matrix, said knives located at points corresponding to the corners of the end flaps of the blank, whereby an incision may be made in each face of said blank at a single operation of said apparatus. 110
11. Apparatus for forming the blanks for folded-blank boxes, including a die and a matrix complementary thereto, said die provided with knives and creasing members and said matrix provided with knives and with depressions complementary to said creasing members, certain of the knives of said die and the knives of said matrix being arranged to produce incisions in said blank from both faces thereof and extending only part way therethrough at a single blank-forming operation. 115
12. Apparatus for forming a blank for folded-blank boxes, including members corresponding to a die and a matrix, a knife carried by one of said members and arranged to produce an incision extending only part way through said blank from one face thereof, and an abutment carried by the other of said members and arranged to support said blank against the thrust of said knife. 120
13. Apparatus for forming a blank for folded-blank boxes, including members corresponding to a die and a matrix, a knife carried by one of said members and arranged to produce an incision extending only part way through said blank from one face thereof, and an abutment carried by the other of said members and arranged to resiliently support said blank against the thrust of said knife. 125
14. Apparatus for forming a blank for folded-blank boxes, including members corresponding to a die and a matrix, a knife carried by one of said members and arranged to produce an incision extending only part way through said blank from one face thereof, and an abutment resiliently mounted in the other of said members and arranged to support said blank against the thrust of said knife. 130
15. Apparatus for forming the blanks for folded-blank boxes and the like, including members corresponding to a die and a ma- 135

- trix, one of said members provided with knives and creasing members, and the other of said members provided with depressions complementary to said creasing members and 5 with knives, certain of the knives of said first mentioned member and the knives of the other member being arranged to produce incisions extending only partway through said blanks from both faces thereof, 10 and resiliently supported abutments carried by said first mentioned member and arranged complementally to the knives of the other member for supporting the blanks under the thrust of the knives of said other 15 member, a single operation of said apparatus sufficing for the functioning of all of said knives and creasing members to produce a finished blank.
16. Apparatus for producing a blank for 20 forming folded-blank boxes and the like containers having a plurality of sides and end sealing flaps, including a die provided with a plurality of cutting knives and creasing
- members suitably arranged therein to produce the cuts and creases requisite to the 25 formation of a blank for boxes of a desired conformation, a matrix provided with depressions complementary to the creasing members of said die, knives carried by said die and arranged to produce surface incisions 30 upon one face of said blank, knives carried by said matrix and arranged to produce surface incisions upon the other side of said blank, all of said knives being so adjusted as to produce incisions extending only partway through the material of said blank and said incisions being so located as to permit peeling of the material of the blank to form webs at the corners of the box produced when said blank is folded.
- In testimony whereof we have hereunto set our hands this 13th day of December 40
A. D. 1926.

JOHN J. GANNON.
FREDERICK W. FOERSTNER.
